UNITED STATES PATENT OFFICE.

EDGAR A. BIENENSTOK, OF MILWAUKEE, WISCONSIN, ASSIGNOR TO MILWAUKEE TANK WORKS, OF MILWAUKEE, WISCONSIN, A CORPORATION OF WISCONSIN.

OIL-VAPOR BURNER.

Application filed October 31, 1921. Serial No. 511,604.

To all whom it may concern:

Be it known that I, EDGAR A. BIENENSTOK, a citizen of the United States, and resident of Milwaukee, in the county of Milwaukee and 5 State of Wisconsin, have invented certain new and useful Improvements in Oil-Vapor Burners; and I do hereby declare that the following is a full, clear, and exact description thereof.

10 My invention is an improvement in oil vapor burners. It contemplates such an arrangement of a gas burner which is used to vaporize oil and an oil vapor burner as to conserve the heat energy involved and direct 15 a maximum to the flat surface of the vapor generator. It contemplates also such an arrangement of parts as will result in a superior operation.

It has also as its object simplicity of construction, strength and readiness of assembly.

20 Other objects will appear as the description proceeds.

Reference is had to the accompanying drawings, in which,

25 Figure 1 is a vertical central cross section of the device.

Figure 2, a plan thereof, and

Figure 3, a side elevation looking from the left of Figure 1.

30 A base member 10 carries headless screw 11, entering a lug 12 for the purpose of making base 10 rigid with the supported parts. Integral with lug 12, are supports 13 and 14 extending upwardly and being continuous 35 with a cross member 15. Support 13 is hollow.

Leading from supply tank 30 is a feed pipe 16 having therein, a needle valve 31 for regulating the flow. Having threaded connection with feed pipe 16 is arm 17 of vapor generator 18. Arm 17 rests upon horizontal portion 19 of support 14. The other end 20 of vapor generator 18 is bolted to cross member 15. At 21, a gasket may be used to make 45 the connection tight.

An annular gas burner 22, having inclined leads 23 thereto, communicates with a gas and air mixer chamber 24 from which a gas connection 25 extends. Gas burner 22 is 50 made rigid with support 14 by a brace 26.

In the operation of the device, oil is admitted, in desired quantity, to the vapor generator 18 by means of needle valve 31. It is there heated to vaporization by the gas

burner 22. The vapor is then conducted 55 through support 13 to vapor burner 33 where it is ignited, the gas supply being turned off. Heat from the vapor burner continues the process of vaporization in the vapor generator to which a supply of oil is regulated 60 by needle valve 31, as explained *supra*.

It is apparent that the spread of vapor generator 18 insures ready vaporization, and the arrangement of burner 22 is conducive to conferring a maximum of heat energy there- 65 to. The location of vapor burner 33 tends also to conserve heat energy. As cross member 15 extends above vapor generator 18, it does not, in any way, impede the operation, yet, at the same time, results in a maximum 70 strength. Vapor generator 18 may be readily separated from or assembled with its support.

I claim:

1. An oil vapor burner comprising a gen- 75 erator, a pair of supports extending upwardly from a base and embracing said generator and continuing across the top of said generator.

2. An oil vapor burner comprising a gen- 80 erator, a pair of supports, one of which is hollow, extending upwardly from a base and embracing said generator and continuing across the top of said generator.

3. An oil vapor burner comprising a pair 85 of supports, one of which is hollow, extending upwardly from a base, said supports being integrally joined together at their lower ends and rigid with said base, and a burner rigid with said supports and immediately 90 adjacent their juncture with the base.

4. An oil vapor burner comprising a vapor burner, a pair of supports extending outwardly and upwardly therefrom, and a lug rigid with said supports and having screw 95 connection with the base.

5. An oil vapor burner comprising an annular gas burner embraced by a pair of supports, and a vapor generator carried by said supports above said annular gas burner. 100

6. An oil vapor burner comprising a pair of supports, one of which is hollow, an annular gas burner embraced and carried by said pair of supports, and a vapor generator carried by said supports above said annular gas 105 burner.

7. An oil vapor burner comprising a flat circular vapor generator, a pair of supports

for said vapor generator, and an annular gas burner positioned below said vapor generator.

8. An oil vapor burner comprising a flat circular vapor generator, a pair of supports therefor, one of which is hollow, a vapor burner rigid with said supports, and an an-

nular gas burner positioned below said vapor generator.

In testimony that I claim the foregoing I 10 have hereunto set my hand at Milwaukee, in the county of Milwaukee and State of Wisconsin.

EDGAR A. BIENENSTOK.
